JOSE F. DE NAVARRO, OF NEW YORK, N. Y., ASSIGNOR TO EMERY ROTARY-MACHINE COMPANY.

Letters Patent No. 78,865, dated June 16, 1868.

IMPROVEMENT IN DEVICES FOR ATTACHING PUMPS TO BARRELS.

The Schedule referred to in these Letters Patent and making part of the same.

TO ALL WHOM IT MAY CONCERN:

Be it known that I, JOSE F. DE NAVARRO, of the city, county, and State of New York, have invented a new and useful Improvement in Devices for Attaching Pumps to Barrels, of which the following is a full, clear, and exact description, reference being had to the accompanying drawing, forming part of this specification, and in which—

Figure 1 represents a longitudinal section of a tapering sleeve, constructed according to my improvement, and as applied to the bung-hole of a cask, with a pump-pipe arranged therein and clamped thereby.

Figure 2, an interior longitudinal view of the one-half or portion of said sleeve, which is made in sections, as hereinafter described; and

Figure 3 an outer end view of the two sections of the sleeve as united, but prior to being closed, as when fitted to the bung-hole to hold or clamp the pipe.

Similar letters of reference indicate corresponding parts.

In pumping liquids or fluids from casks, barrels, and other like close vessels, it is not only necessary that the pipe of the pump should be projected through the bung-hole, to or near the bottom of the cask, but that said pipe should be clamped or held steady, more especially at its fit through the bung-hole, to withstand the shocks and vibrations consequent upon pumping, with adequate provision against leakage. This has, in part, before been met by the employment of a threaded nut or collar on the pipe, arranged to screw into the bung-hole; also by the use of a loose screw-sleeve, of conical form on its exterior, and provided with a set-screw at its side for clamping the pipe, which is passed loose through the sleeve, that serves as a plug to the bung-hole. But my invention essentially differs from both of these previous devices, by employing a loose screw-sleeve of conical or taper form, made in longitudinal sections or halves, dowelled together, to guide them in meeting or approaching each other, and provided with air-ducts or passages, and clamping-ribs or formations internally, so that the screwing of the two sections into or through the bung-hole of the cask will cause the divided sleeve to firmly hold and gripe the pipe in a divided manner, as regards its biting surface on the latter, thus preventing injury to the same, and whereby the necessity of working or adjusting a separate clamping-screw is avoided, and the device made automatically to accommodate itself to different sizes of pipe and diameters of bung-hole.

Referring to the accompanying drawings, A A' are the two halves or sections of my improved sleeve, of conical or taper form, when brought together, and preferably with a screw-thread on their exterior, said sections being guided and held together by suitable dowel-pins, a, projecting from the one section, and arranged to freely fit corresponding holes in the other section, also being furnished, say, with handles or ears, b, or otherwise suitably constructed, to facilitate the screwing of the split sleeve into the bung-hole. These sections, A A', are constructed internally with air-ducts, c, running down or through them, and with ribs or gripping-surfaces, d, arranged to clip the pipe in an easy and spread or divided manner at different points or lines around, throughout, it may be, the greater portion of the pipe, or portion of the same passing through the sleeve.

In this way is the pipe firmly clamped without injury to its surface, and the grip of the same automatically established, that is, by the mere act of screwing the split sleeve into or through the bung-hole, and the device made readily to adapt itself to different sizes of bung-holes and pipes without depriving it of the necessary air-vent or vents.

Said suction-pipe may be extended to the lower level or bottom of the cask, and be perforated at its sides, or otherwise suitably constructed, to allow of the free ingress of the liquid through or near its bottom.

What is here claimed, and desired to be secured by Letters Patent, is—

The clamping-sleeve A, of two or more parts, dowelled together, and of conical exterior, with internal gripping-ribs or projections, for clamping the suction-pipe of the pump, substantially as shown and described, for the purpose set forth.
